UNITED STATES PATENT OFFICE.

GILBERT WAYNE RUGGLES, OF YOUNGSTOWN, OHIO.

EXTENSION GRATE APPARATUS.

Application filed November 26, 1920. Serial No. 426,342.

To all whom it may concern:

Be it known that I, GILBERT WAYNE RUGGLES, a citizen of the United States, and a resident of Youngstown, county of Mahoning, and State of Ohio, have invented a new and useful Improvement in Extension Grate Apparatus, of which the following is a specification, the principle of the invention being herein explained and the best mode in which I have contemplated applying that principle, so as to distinguish it from other inventions.

My invention relates to an extension grate apparatus and more particularly to the construction of the connecting and driving members therefor.

Heretofore, difficulty has been experienced in disconnecting and removing a grate for cleaning out coal and ash from the grate bearers and for repairing such grate bearers and the grate structure. Much time and labor has been thus consumed and the operation of the boiler and its associated mechanism has been greatly interfered with. Also, where the parts are not readily removable the air space of such apparatus is permitted to become filled with coal or ash, greatly affecting the proper combustion of the fuel and the efficient working of the apparatus.

The object of my invention is to obviate the disadvantages mentioned and to provide an improved means of connecting and driving the extension grate of an underfeed stoker type of furnace. To the accomplishment of the foregoing and related ends, the said invention, then, consists of the means hereinafter fully described and particularly pointed out in the claims.

The annexed drawing and the following description set forth in detail certain mechanism embodying the invention, such disclosed means constituting, however, but one of various mechanical forms in which the principle of the invention may be used.

The single figure of the drawing is a longitudinal sectional elevation showing my improvement applied to a grate structure of the type mentioned.

The grate forms a part of a furnace for steam boiler plants of the self-feeding type wherein stepped grate bars are used.

The parts illustrated show the grate bearer member 1, providing a chamber 2 of greater depth at its rearward portion to accommodate the operating levers for reciprocating

the grate and a shallow chamber 3 forwardly thereof to serve as a guide-way for the operating member or link 4 of the slide or extension section 5 of the grate structure. A single central link may be employed or a plurality of spaced links as desired. The grate proper is supported upon a frame 6 comprising a casting having a base section provided with extensions 7 for slidably engaging guide-ways upon the grate bearer lateral walls 8, and an intermediate supporting web 9. The grate is made up of a series, or may comprise a plurality of such series of superposed plates 10 presenting, when assembled in place, the effect of a series of shallow steps. These plates are removably secured to the supporting frame which has suitably placed securing lugs 11 thereon. At the top of the series of plates is provided a removable nose 12 bolted to the furnace frame 21 and replaceable in the event of its being damaged by heat. The plates are supported so as to leave openings 13 between the lower end of each and the top of the one below, through which an air blast may be passed by the draft mechanism of the furnace. Attached to the outer vertical wall of the frame is an inwardly extending supporting arm 14, which provides a bearing for a transverse shaft 15 to which is attached a rocker arm 16 for the shaft and a shorter arm 17 with a pivot connection at its lower end for attachment to the grate operating link 4. The inner end of this link is provided with an enlargement 18 of circular cross-section in the upper face of which is formed a slot 19 of greater width at its bottom than at the surface. The frame member of the extension grate has secured to the outer portion of its under side, by means of bolts, an angle iron 20, one flange portion of which is adapted to enter the slot in the link member. Through the oscillation of the shaft, it will be noted, the link member will be reciprocated and will carry with it the extension grate frame member, the enlarged bottom portion of the slot preventing cramping action of the sides of the slot upon the link angle engaged therein, through the angularity of its motion and at the same time there will be no lost motion caused.

The grate frame 6 has a sufficient amount of play between it and the grate bearer member 1 so that it may be lifted or rocked

2

sufficiently to allow the angle iron 20 to be raised out of the slot 19, thus allowing the frame member to be moved out away from its support. To return the grate frame member to its place, it is merely forced back into position and then lifted sufficiently to allow the angle iron to be placed in engagement with the slot. In former types of extension grates the operating link was connected to the grate frame by means of a pin or other fastening which was relatively inaccessible and hard to remove or connect. The weight of the frame with its associated grate bars serves to hold it upon the grate bearer member, and the provision of the chamber 3 as a guideway prevents accidental disengagement of the link and angle iron and allows the normal operation of the device in the usual manner. Should it at any time become desirable to disassemble the parts, it may thus be easily accomplished, inasmuch as the angle member will freely lift out of the slot in the operating link. In this way, access may be quickly had to the interior of the grate or grate bearer member and the air space may be prevented from being filled with coal or ash and necessary repairs may be accomplished with a minimum loss of time and expenditure of labor.

Other modes of applying the principle of my invention may be employed instead of the one explained, change being made as regards the mechanism herein disclosed, provided the means stated by any of the following claims or the equivalent of such stated means be employed.

I therefore particularly point out and distinctly claim as my invention:—

- 40 1. In a mechanical stoker, the combination of an extension grate, a member adapted to slidably support same, a reciprocable link, said grate being tiltable relatively to said member, and operating connections between said grate and link adapted to be disengaged upon such tilting of the grate.
- 45 2. In a mechanical stoker, the combination of an extension grate, a member adapted to slidably support said grate, a reciprocable link having an upwardly opening slot and a transverse element secured to said grate and engaging with such slot, said grate being

tiltable relatively to said supporting member in order to disengage said element from such slot and thereby permit removal of said grate.

3. In a mechanical stoker, the combination of an extension grate, a member adapted to slidably support said grate, a reciprocable link having an upwardly opening slot, such slot being of greater width at its lower portion, and a flange depending from said grate and engaging with such slot, said grate being tiltable relatively to said supporting member in order to disengage said flange from such slot and thereby permit removal of said grate.

4. In a mechanical stoker, the combination of an extension grate, a member adapted to slidably support said grate, a link reciprocably resting on said support and having an upwardly opening slot, guide means for said link, and a transverse element secured to said grate and engaging with such slot, said grate being tiltable relatively to said supporting member in order to disengage said element from such slot and thereby permit removal of said grate.

5. In a mechanical stoker, the combination of an extension grate, a link having a slot in one end portion thereof, an angle plate secured to said grate and having one edge portion in said slot, a slideway supporting said end portion of the link so as to maintain an operative engagement between the same and said edge portion of the angle plate, and means for reciprocating the link.

6. In a mechanical stoker, the combination of an extension grate, a member adapted to slidably support said grate, a link reciprocably resting on said support and having an upwardly opening slot, guide means for said link, a transverse element secured to said grate and engaging with such slot, said grate being tiltable relatively to said supporting member in order to disengage said element from such slot and thereby permit removal of said grate, a rock-shaft, and a crank-arm on said shaft connected with said link in order to reciprocate same.

Signed by me, this 22nd day of November, 1920.

GILBERT WAYNE RUGGLES.
